INFLATABLE SECTIONAL TENT

Edwin B. Katzenmeyer, Akron, and Carroll P. Krupp, Cuyahoga Falls, Ohio, assignors to The B. F. Goodrich Company, New York, N. Y., a corporation of New York

Application November 1, 1950, Serial No. 193,348

15 Claims. (Cl. 135—1)

1

This invention relates to inflatable structures for shelter purposes and especially to inflatably supported, sectional tents, lodges, huts, buildings and other shelter structures.

Prior unitary inflatable shelters such as relatively large tents having the side walls, or the roof, or both of rubber-treated textile fabric and double-wall, pocketed construction throughout, and prior portable huts, houses, lodges, and other shelters of the pre-fabricated type of solid, stiff material such as wood, steel, aluminum and the like, have not been entirely satisfactory for the intended purpose. The inflatable shelter has required an objectionably large volume of air and extensive time for inflation, and has tended to sag or collapse in use because of substantial leakage of the inflating air through the extensive, dual walls. The pre-fabricated shelters have been so complicated, heavy and bulky as to require special heavy-duty vehicles for their transportation, expensive foundations, skilled workmen for their assembly, and an objectionable amount of time to assemble.

An object of the invention is to overcome the foregoing and other disadvantages of the prior shelter constructions.

Other objects of the invention are to provide an improved, inflatably-supported, shelter structure such, for example, as a tent or other building having one or more sections of impervious, flexible, non-metallic, sheet material; to provide for a single-wall, sectional construction of durable, lightweight, inflatable character; to provide for assembling and separably attaching adjacent sections of the shelter structure to one another without requiring skilled workmen; to provide for individual support and mounting of a section of the shelter structure and for coaction of the supporting means of adjoining sections; to provide for weather-proofness, air and light-tightness, foldability and portability of the tent or other shelter structure; and to provide for simplicity of construction, convenience of manufacture and assembly, and for effectiveness of operation.

Further objects are to provide for minimizing the volume of inflating medium required to support the tent and at the same time, to provide for maintaining effectively the tent in a desired shape and a taut and upright condition; to provide for conveniently and individually inflating each sectional unit of the tent and for minimizing loss of inflating medium; to provide for strong, reliable joint connections of adjacent sections of the tent; to provide for fastening adjacent sections detachably together so as to per-

2

mit making tents of various sizes; to provide for an inflatable main frame or truss and stringer or strut assembly capable of supporting a flexible, single-thickness covering or wall of a sectional unit of the tent and capable of resisting stresses tending to collapse the flexible wall; to provide for supporting the flexible wall of the tent along a plurality of spaced-apart lines intersecting one another at positions spaced-apart 10 longitudinally and transversely of the tent as a whole; to provide for an inflatable support assembly for each section including a transversely-extending arch-type beam; and to provide for an inflatably supported end wall construction and for separably attaching the end wall to an adjacent sectional unit of the tent.

Still further objects are to provide for conveniently mounting the tent upon a supporting surface which may be bare ground, or a ground cloth, or a wood platform, or a concrete strip, or other suitable surface; to provide for expeditiously assembling the sections of the tent and for simultaneously inflating the individual sections; and to provide for small bulk of the packaged sections of the tent in the deflated condition.

These and other objects and advantages of the invention will be apparent from the following description:

30 In the accompanying drawings which form a part of this specification,

Fig. 1 is a side elevational view of an inflatably supported, sectional tent and its inflating manifold, constructed in accordance with and embodying the invention, parts being broken away,

Fig. 2 is an elevational view of the tent including an inflatably supported end wall construction having a door therein, as viewed from the left hand end of the tent, parts being broken away,

Fig. 3 is a plan view of the tent, parts being broken away,

Fig. 4 is a perspective view of individual main frame assemblies disposed for attachment to one another, the outer covering of the tent being removed,

Fig. 5 is a sectional view in an enlarged scale taken along line 5—5 of Fig. 3,

Fig. 6 is a sectional view in an enlarged scale taken along line 6—6 of Fig. 1 showing a joint construction at sectional units intermediate the ends of the tent,

Fig. 7 is a sectional view in an enlarged scale taken along line 7—7 of Fig. 3,

Fig. 8 is a sectional view in an enlarged scale

taken along line 8—8 of Fig. 3 showing a joint construction at one end of the tent.

Fig. 9 is a sectional view of an end closing and mounting construction of the arched beam of a main frame assembly.

Fig. 10 is a modification of the joint construction shown in Fig. 6.

Fig. 11 is a modified construction of the main frame assembly shown in Fig. 4.

The elongated, sectional shelter or tent 15 shown in the drawings, has an outer covering or wall 16 formed of a plurality of separably interconnected sections or panels 17, 18, and 19 having their adjacent end margins in juxtaposition and providing spaced-apart sidewalls 20, 21 and a roof 22 therebetween of single thickness and of impervious, flexible, non-metallic, sheet material such, for example, as square-woven textile fabric of nylon, fiberglass, rayon, cotton, silk, linen, or combinations thereof coated or impregnated or otherwise treated with rubber, natural or synthetic, or other rubber-like material such as rubbery polychloroprene and, if desired, protected on the outside with a thin coating of aluminum flakes or powder applied as by a printer's roll. The sectional outer covering 16 may be made of single thickness, rubber coated, square-woven, textile fabric of nylon filamentary material, and is maintained and supported as a whole in a taut, upright condition, despite its collapsible character, by a plurality of inflatable support assemblies or main frames 23, 24, and 25 disposed vertically and arranged in series in the longitudinal or fore and aft direction of the tent 15 and separably attached to one another in end to end relation so that any desired number of sections and length of the tent 15 can be provided.

The interconnected inflatable main frames 23, 24, 25 and an inflatable arched beam 26 at one end of the tent constitute, in the inflated condition, a stiff, articulated supporting framework of inflatable tubular elements for the collapsible, flexible outer covering 16, to which framework the respective sections or panels 17, 18, 19 of the outer covering may be attached along tubular transverse trusses or beams 27, 28, 29 of the main frames, in a manner described more fully hereinafter and as shown especially in Fig. 5, so that each covering section in its taut upright supported condition comprises a plurality of successive intersecting planes or planar portions with the included angle at each intersection being less than 180° at the interior face thereof, and desirably with the lines of intersection all being substantially parallel to each other, as shown especially in Figs. 1, 2 and 3. Each main frame and its attached section or panel covering provide a complete, individual sectional unit or structure of the tent, and the individual sectional structures are disposed end to end in series along the tent.

The inflatable main frame of each sectional structure, 17 and 23, 18 and 24, 19 and 25 of the tent has a transverse truss or beam 27, 28, 29, preferably of arched or inverted, generally U-shaped form in the inflated condition, as viewed from an end of the tent, and as shown especially in Figs. 2 and 4. The arched beam 27 of the basic individual, sectional unit or structure 17, 23, for example, constitutes the primary load-carrying member of the main frame 23, and is made, preferably, unitary and tubular and of suitable impervious, flexible, non-metallic sheet material having the desired strength, weather-resistance,

low-elongation, and distensibility characteristics. The material may be square-woven, cotton or rayon fabric coated or otherwise treated with suitable rubber material such as rubbery polychloroprene, which treated fabric is advantageous for its light-weight, durability and impermeability, resistance to bursting and tearing, and extensive flexibility and distensibility.

All the tubular arched beams 26, 27, 28, 29 which are disposed vertically and extend transversely of the tent, are mounted at the closed ends of the beams on supporting caps 30, 30 disposed on a suitable supporting surface or foundation 31 such, for example, as a concrete strip, a wooden base or floor, substantially flat ground, or other suitable firm surface, as shown especially in Figs. 1, 2, 3 and 9. Each arched beam, by virtue of its inflation and tubular construction, has great stiffness throughout its extent between the mounting positions at the closed ends of the beam, which stiffness is advantageous to resist objectionable buckling and bending of the main frame assembly and collapse of the sectional unit of the tent.

The arched beam 27 of the basic sectional structure 17, 23 of the tent has spaced-apart, sidewall-supporting tubular portions 32, 33 and a roof-supporting tubular portion 34 interconnecting adjacent ends of the sidewall-supporting portions in integrally united, fluid-tight relation to the same, each of which portions 32, 33, 34 of the beam, preferably though not necessarily, increases gradually in diameter or tapers radially outward from opposite ends of the portion toward the center region indicated at 35, 36, 37 of the portion, as shown especially in Figs. 2 and 4. The dual tapered construction is advantageous for increased load-carrying capacity with a lesser amount of fabric material as compared to that of the modified construction shown in Fig. 11 wherein in all the aforesaid portions of the arched beam are of substantially uniform and the same diameter. The dual tapered construction of the arched beam not only requires less fabric material as compared to the uniform diameter type of construction but at the same time, provides superior resistance to buckling and bending and to sway laterally of the tent and provides increased strength in tension and compression, in the inflated condition; and has distinct advantages for use in tents of large size which subject the inflatable main frames to heavy static and dynamic loads, especially high wind loads.

Each sidewall-supporting portion 32, 33 and the roof-supporting portion 34 of the beam may be made such that the longitudinal axis, indicated by the numeral 38, of the portion in the vertical plane of the beam is inwardly bent at approximately the center region or midpoint at 35, 36, 37 between the ends of the portion so that the tapered parts of the portion are inclined slightly relative to one another, as viewed from an end of the tent and shown especially in Fig. 2. For example, the included angle of the bent axis of the respective sidewall-supporting portions indicated at C may be about 155° and the included angle of the bent axis of the roof-supporting portion indicated at D may be about 166°. The arrangement makes feasible a tent of approximately hexagon shape in cross-section, excluding the base or surface 31 for mounting the tent. The hexagon shape advantageously provides a ridged roof contour of flat pitch for facilitating the shedding of rain and snow;

provides an inwardly inclined contour of the upper parts of the sidewalls for further facilitating the shedding of rain and snow; and at the same time, provides for reducing the wind pressure and other live loads on the tent as a whole.

Gussets 39, 39 of suitable rubber-treated, square-woven fabric and triangular form may be disposed axially of the beam and secured as by sewing, or a suitable air-drying rubber cement, or both to the fabric material of the arched beam at the junctions of the sidewall-supporting portions with the roof-supporting portions, as shown especially in Fig. 2, for further strengthening the beam against objectionable sway and flexure of the arched beam in the direction transversely of the tent. Preferably, only the beams 28, 29 of the intermediate main frames 24, 25 are provided with the gussets.

The closed lower ends of the sidewall-supporting portions of the arched beam 27, for example, have a molded, closed end plug 40, 40 of hard rubber or other stiff plastic material adhesively secured therein and are desirably mounted detachably in the supporting caps 30, 30 of stiff, strong material such as a suitable metal or thermosetting plastic resin or other stiff material and desirably of cupped and flanged based construction, which caps 30, 30 rest firmly on the supporting surface 31, as shown especially in Figs. 1, 2, 3 and 9, and constitute protective bases of the beam adapted to transmit and distribute the load to the supporting surface 31.

The respective inflatable main frames 23, 24, 25 have a plurality of longitudinally-extending, transversely spaced-apart, connecting struts or tubular stringers (41, 41) (42, 42) (43, 43) of suitable rubber-treated, square-woven cotton or rayon fabric and desirably of substantially uniform and relatively less diameter than that of the arched beam. The struts project perpendicular to the plane of the longitudinal axis of the beam substantially parallel to one another and constitute the secondary load-carrying members of the main frame. The struts are fixedly secured at one of their ends to the arched beam at one side thereof in air-tight relation as by a flange 44 and overlying fabric tape 45 construction adhesively attached thereto and are in communication therewith through an aperture 46 in the wall of the beam, and extend toward the adjacent main frame of the tent, as shown especially in Fig. 6, for example, and are sealed air-tight at the other or attaching end, as shown in Fig. 6, and described more fully hereinafter. The struts are disposed spaced-apart along the beam at desired positions thereon so as to facilitate the provision of a substantially smooth, hexagon-shaped exterior of the tent.

In the embodiment shown in Figs. 1 to 9, one of the struts, for example, a strut 41 of the main frame 23 is located at each junction of the sidewall-supporting portions 32, 33 with the roof-supporting portion 34 of the arched beam 27. One of the struts 41 is located at the midpoint or region of maximum diameter at 35, 36, 37 of each sidewall-supporting portion and desirably the roof-supporting portion. Preferably, the lowermost of the struts 41 is located approximately midway of the lower part i. e. midway between the closed lower end and the region of maximum diameter of each sidewall-⁷⁵

supporting portion 32, 33 of the beam, although, as shown in Fig. 11, the strut may, if desired, be disposed at the closed lower ends of the arched beam.

5 The struts, in the inflated condition, not only resist stresses longitudinally of the tent but also function as ties and spacers of uniform length between adjacent arched beams. Also, the struts provide continuity of support to the 10 collapsible outer covering between adjacent beams along longitudinally-extending, transversely spaced-apart lines for preventing inward bulging of the covering and for facilitating maintenance of the collapsible covering in its 15 taut and upright condition.

Each tubular strut 41, 42, 43 at its free or attaching end is sealed fluid-tight by a sleeve 47 and closed end plug 48 fitting of stiff, impervious material such, for example, as hard rubber, thermosetting plastic resin, aluminum or other suitable stiff material, the fitting 47, 48 being disposed, as shown in Fig. 6, within the tubular end portion of the strut in overlapping relation thereto and adhered to the fabric material of the strut 20 as by a suitable rubber cement of the air-curing type. The exposed end portion 49 of the sleeve 47 has a curved configuration in section for seating conformingly against the curved wall of the adjacent arched beam in the inflated condition 25 so as to provide for good support of the closed end of the strut by a substantial area of the beam.

For separably attaching the strut 41, for example to the adjacent arched beam 28, a flexible strap 50 of suitable rubber-treated fabric and a 30 slotted covering patch 51 of suitable rubber-treated fabric are suitably adhered to the exterior of the end portion of the strut at the region of the sleeve and plug fitting 47, 48 and at each of diametrically opposite zones of the end portion 40 in alignment with the longitudinal axis of the tubular strut, as shown in Fig. 6. A looped flexible strap 52 of suitable rubber-treated fabric having a suitable metal buckle 53 held by the looped portion of the strap and a slotted covering 45 patch 54 of suitable rubber-treated fabric are adhesively attached to the exterior of the arched beam at each of spaced-apart positions thereon to opposite sides of the strut and in alignment with the longitudinal axis of the tubular strut for facilitating the engagement of the straps 50, 50 on the strut 41 with the buckles 53, 53 so as to fasten detachably the closed end portion of the strut 41 to the arched beam 28 while the curved end 49 of the stiff sleeve 47 is disposed in conforming relation against the distended wall of the arched beam. The arrangement advantageously makes feasible the secure, separable attachment of the closed end of the strut to the adjacent arched beam and at the same time avoids objectionable looseness and wobble of the connection and localized stresses on the beam by the closed end of the strut.

Adjoining sections 17, 18, 19 of the flexible outer covering 16 of the tent are arranged end to end and connected one to the other and to an arched beam 28, 29 intermediate the ends of the tent in the manner shown in Fig. 6. The outer covering section 18 to the left of the arched beam 28, as shown in Fig. 6, is fixedly secured to the beam at its outer side throughout its full length by crotch tapes 55, 56 of suitable rubber-treated fabric extending along the beam at positions spaced-apart laterally of the beam and adhesively secured, or sewed, or otherwise attached to both the beam 28 and the left hand covering section

18, the crotch tape 56 to the right of the beam having a short slit therein to accommodate the looped portion of the strap 52 at the outer side of the beam.

The left hand covering section 18 extends to the right a short distance beyond its connection to the beam 23 at the right hand crotch tape 56 to provide an attaching end margin 57 to which desirably a flexible stringer 58 of suitable rubber-treated fabric having slide fastener teeth 59, 59 thereon is secured as by stitches 60, 60 of suitable thread, or by a suitable rubber cement, or both. The margin 61 of the right hand covering section 17 at the free end thereof has suitably secured thereto a suitable stringer 62 having slide fastener teeth 59, 59 for engaging the teeth 59, 59 of the left hand covering margin 57, a separable slider (not shown) being provided for engaging and disengaging the teeth of both margins. A cover flap 63 of suitable rubber-treated fabric is desirably suitably secured to the outer side of the margin 57 of the left hand covering section 18 for disposition in overlapping relation to the engaged teeth 59, 59 and part of the margin 61 of the right hand covering section 17 for closing the connection between the sections 17, 18 against the passage of light, rain or snow, and wind between the spaces of the engaged teeth.

Each intermediate sectional unit including the lefthand end sectional unit of the tent has its panel 18, 19 of the flexible outer covering mounted and fixedly attached to the arched beam 28, 29 of the unit, as described hereinabove and shown especially in Figs. 5 and 6, in a manner to facilitate the separable attachment of the panels 18, 19 to one another and to the panel 17 of the right hand end or basic sectional unit of the tent shown especially in Figs. 1 and 3.

The basic sectional unit or assembly 17, 23 to which the intermediate sectional units or assemblies are connected in series, differs in several respects from the construction of the intermediate unitary sectional assembly. The basic unit has the outer covering panel 17 adhesively attached, or sewed, or both directly to the fabric material of the arched beam 27 and terminated at the beam, as shown especially in Fig. 7. Also, it differs in that no gussets 39 are required and has an end wall 64 of suitable rubber-treated, square-woven fabric adhesively attached to the beam as by a flange portion 65 and suitable tape 66 throughout the length of the beam 27 at a position diametrically opposite the attachment of the outer covering 17 so as to be disposed taut and vertically dependent of the tent across the entire right hand end opening of the tent defined by the beam 27.

For closing the left hand end and completing the inflatable framework of the tent shown in Fig. 1, the invention provides the arched beam 26 and end wall 67 assembly adapted for separable attachment to the adjacent left end or intermediate unitary sectional assembly. The arched beam is constructed as described hereinabove, but has no communicating struts and only a relatively narrow strip 68 of the outer covering material suitably attached at one margin thereof to the beam 26 with a suitable stringer 69 and teeth 59, 59 along the free margin of the strip 68 for engagement with the teeth 59, 59 of the slide fastener of the adjacent panel 19 of the tent as shown especially in Fig. 8. The end wall 67 of suitable rubber-treated, square-woven fabric is suitably secured to the arched end beam 26 along the same at a position opposite the attachment

of the strip 68 of outer covering so as to be held in a vertically dependent, taut condition, and has a suitable tape reinforcement 95 adhesively secured to the beam and the end wall as shown in Fig. 8. Suitable looped straps 52, 52 and buckles 53, 53 are attached to the beam 26 as by patches 54, 54 at positions spaced-apart along the beam for connection to the straps 50, 50 of the struts 43, 43.

10 The end wall 67 at its lower central region may have a suitable opening for entrance into the tent, the side margins 70, 71 of the wall at the opening having desirably suitable stringers and teeth for separable engagement with cooperating teeth on the side margins of a flexible door 72 of suitable rubber-treated, square-woven fabric for closing the entrance opening. The door is desirably fixedly attached across its top to the top margin 73 of the end wall at the opening, 15 as shown especially in Fig. 2. The arrangement facilitates quick closure of the opening and convenience of entrance to and egress from the tent.

A plurality of attachment patches 74, 74 of suitable rubber-treated, square-woven fabric and 20 metal D-ring construction may be adhesively or otherwise suitably attached to each arched beam approximately midway of the sidewall-supporting portions thereof such that the D-rings are positioned at the exterior side of the covering panel, 25 and also are attached to the respective arched beams at the ends of the tent at the respective ends and midway locations of the roof-supporting portions, as shown especially in Figs. 1, 2, 3, and 7, for facilitating the attachment of suitable 30 flexible guy wires or flexible bracing ropes (not shown) of nylon, hemp or other filamentary material to the beams at the exterior of the tent to hold the tent tied down to the mounting surface.

For inflating the main frame 23, 24, 25 of each 35 sectional unit of the tent, desirably all frames and the left end arched beam 26 in a simultaneous manner, each arched beam at a position adjacent its lower end and at the same side of the tent has a suitable inflating fitting 75 in 40 communication with the beam and adapted for separable connection to a flexible connecting tube 76 of reinforced rubber tubing construction, for example, which connecting tube 76 is adapted for 45 separable connection to a suitable inflating fitting 77 on a flexible inflation manifold 78. The inflation manifold 78 which may be of suitable 50 rubber-treated, square-woven fabric, has closed ends and a plurality of the inflating fittings 77, 77 spaced-apart along the manifold at positions 55 corresponding to the positions of the arched beams 26, 27, 28, 29 for connection to the connecting tubes 76, 76, and also has a suitable 60 inflating fitting 79 desirably intermediate the closed ends for connection through a suitable flexible 65 conduit 80 to a source of fluid under pressure such as air (not shown). A pressure relief valve 81 may be mounted on the manifold to prevent an inflation pressure in the main frames 23, 24, 25 sufficient to burst the inflated beams and 70 struts while permitting sufficient inflation pressure such, for example, as three pounds per square inch (3 lbs./p. s. i.) to be maintained in the beams and struts to retain the tent in the desired upright, taut condition without objectionable sagging of the outer covering 16.

The embodiment of the tent shown in the drawings having a plurality of sectional units is relatively light-weight and can be compactly packaged in relatively small containers, both of 75 which features are advantageous for shipping as

by a transport plane; yet the tent can be quickly and conveniently assembled at the desired location and mounted on the supporting surface without requiring skilled workmen such as carpenters and the like. The tent can be inflated to its upright, taut condition in a matter of minutes as compared to several days which are generally required for erecting portable shelter structures of plywood and aluminum construction. Also, the tent can be erected with any number of sectional units thereby making it adaptable to a variety of uses such, for example, as a briefing tent to house photographic processing apparatus and a picture projecting theater capable of housing a large number of persons.

The modified joint construction shown in Fig. 10 differs from the construction shown in Fig. 6 in that connecting sleeves 82, 83 of suitable stiff material are adhesively secured at their end flanges to the arched beam at diametrically opposite, aligned positions thereon so that the sleeves 82, 82 project radially outward from the beam 28 for connection to the struts 41, 42. The sleeve 82 at one side of the beam is in communication therewith and has the strut 42 of the main frame 24 mounted telescopically over the outside of the sleeve in sealed, adhered relation to the same.

The strut 41 of the adjacent main frame 23 to be connected to the beam 28 is closed by a suitable plug 84 of the stiff material inserted into the end portion of the strut 41 and suitably adhered to the strut, the assembled plug and end portion of the strut being adapted to be inserted telescopically and detachably into the other sleeve 83 mounted on the beam. The arrangement facilitates the attachment of the aligned struts, one fixedly and one detachably, to the arched beam. The arched beam 26 at the left end of the tent may also be provided at one side only with suitable flanged sleeves 83 mounted for receiving the assembled plug and end portion of the struts 43, 43 of the adjacent main frame 25. Instead of the flap 63, for covering the slide fastener means, the slide fastener teeth 59, 59 at each margin 57, 61 of the connected panels 17, 18 may have resilient rubber sealing strips 85, 85 of tapered construction mounted directly on the teeth to close the margins by lip-action sealing of the strips.

The modified inflatable main frame construction shown in Fig. 11 provides for a pentagon shape in cross-section of the tent. The tubular arched beam 86, 87 of each main frame 88, 89 is of relatively large, substantially uniform diameter throughout its length rather than of the tapered construction shown especially in Fig. 4. The tubular struts 90, 90 and 91, 91 of the main frame 88, 89 are of smaller diameter than the beam 86, 87 and are mounted at different positions on the beam 86, 87 than for the tapered construction, one each being at the ends of the beam, at the junction of the vertical lower part with the inclined upper part of the sidewall-supporting portions 92, 93 of the beam, and at the junction of the sidewall-supporting portions with the roof-supporting portion 94 of the beam. The arrangement, except as noted above, is otherwise like that of the main frames of the embodiment shown in Fig. 1 and provides for directly connecting the ends of the spaced-apart beams to one another and is suitable for relatively small tents wherein light loads are carried by the main frames.

While the tent shown in the drawings is of uniform width and height and polygonal shape in cross-section along its length, it is to be understood that the main frames may be dimensioned

to vary the width and height and shape for providing other suitable shapes such, for example, as a tapered arrangement of the tent as a whole or in part.

Variations may be made without departing from the scope of the invention as it is defined in the following claims.

We claim:

1. An inflatable shelter comprising a sectional covering having sections of flexible material providing sidewalls and roof of the shelter, an inflatable tubular supporting framework having an articulated sectional construction and arrangement disposed in supporting relation to said covering at the sidewalls and roof portions thereof to maintain the flexible covering upright, and means for inflating said supporting framework.
2. An inflatable shelter as defined in claim 1 in which the sections of said sectional covering have margins adjoining and separably attached one to the other, and in which the sections of said framework are separably attached to one another, each section of said framework being associated with one of said sections of said covering for supporting the same upright.
3. An inflatable shelter comprising a sectional covering of flexible material providing sidewalls and roof of the shelter, a sectional supporting framework of interconnected inflatable tubular elements disposed in supporting relation to said covering at the sidewalls and roof portions thereof to maintain the flexible covering upright, and means for inflating said tubular elements of said framework, a section of said covering and a section of said framework associated with the covering section constituting together an individual sectional structure having ends, said shelter having the individual sectional structures thereof disposed end to end in attached relation to one another.
4. An inflatable shelter comprising a sectional covering for mounting upright to provide sidewalls and roof of the shelter and having sections of flexible material in series along the shelter with margins in juxtaposition and separably joined, and a supporting framework comprising inflatable main frames in series along the shelter for maintaining the flexible covering upright, each main frame supporting a section of said covering and having inflatable tubular elements in communication with one another extending along the sidewalls and roof portions of the covering section in supporting relation thereto, means for separably attaching said main frames to one another, and means for inflating said main frames.
5. An inflatable shelter comprising a sectional covering having sections of flexible material in series along the shelter with margins in juxtaposition and separately joined, a supporting framework for maintaining the flexible covering upright to provide sidewalls and roof of the shelter, said framework comprising inflatable main frames in series along the shelter; each main frame being connected with and supporting a section of said covering, each main frame comprising an inflatable tubular element extending transversely of the shelter along the sidewalls and roof portions of the covering section in supporting relation thereto and a plurality of inflatable tubular elements disposed spaced-apart along the first said tubular element in communication therewith and projecting therefrom at a side thereof longitudinally of the shelter toward the adjacent main frame in supporting relation

11

to said sidewalls and roof portions of the covering section, means on all said inflatable tubular elements for separably attaching the same to said adjacent main frame, and means for inflating said main frames.

6. An inflatable shelter comprising a sectional covering of flexible material for mounting upright to form sidewalls and roof of the shelter, a sectional supporting framework for maintaining said covering upright and comprising inflatable main frames each supporting a section of said covering and constituting therewith an individual sectional structure having ends, said shelter having the individual sectional structures thereof disposed in end to end relation along the shelter, means for separably attaching said individual sectional structures one to the other in the end to end relation, and means for inflating said inflatable main frames.

7. An inflatable shelter comprising individual sectional structures having ends and disposed end to end along the shelter in separably attached relation to one another, each individual sectional structure comprising a covering section of flexible material for mounting upright to provide sidewalls and roof of the shelter and an inflatable main frame attached to said covering section for supporting the same upright, said main frame comprising an inflatable tubular beam extending transversely of the shelter adjacent one end of the sectional structure and extending continuously along the sidewalls and roof portions of said covering section in supporting relation thereto and said main frame comprising a plurality of inflatable tubular struts spaced-apart along said beam in communication therewith and projecting longitudinally of the shelter from said beam at a side thereof toward the other end of the sectional structure in supporting relation to said portions of said covering section, means for separably attaching said individual sectional structures to one another, and means for inflating said main frame of each individual sectional structure.

8. An inflatable shelter as defined in claim 7 in which said covering section of the individual sectional structure in the upright supported condition comprises a plurality of successive intersecting planar portions, the included angle at each intersection being less than 180° at the interior face of said planar portions and the lines of intersection all being substantially parallel to each other, and in which said tubular beam of the inflatable main frame has a relatively greater diameter than that of said tubular struts and conforms to said planar portions of said covering section in the inflated condition of said main frame.

9. An inflatable shelter as defined in claim 7 in which said covering section of the individual sectional structure in the upright supported condition comprises six successive intersecting planar portions, the included angle at each intersection being less than 180° at the interior face of said planar portions and the lines of intersection all being substantially parallel to each other, and in which said tubular beam of the inflatable main frame has a relatively greater diameter than that of said tubular struts and has integrally united tapered portions in series conforming to said planar portions of said covering section in the inflated condition of said main frame, and in which said tubular struts are of substantially uniform diameter and extend substantially parallel to one another longitudinally of the shelter.

10. An inflatable shelter as defined in claim 7

12

in which said covering section of the individual sectional structure in the upright supported condition comprises five successive intersecting planar portions, the included angle at each intersection being less than 180° at the interior face of said planar portions and the lines of intersection all being substantially parallel to each other, and in which said tubular beam of the inflatable main frame has a relatively greater diameter than that of said tubular struts and is of substantially uniform diameter throughout and conforms to said planar portions of said covering section in the inflated condition of said main frame, and in which said tubular struts are of substantially uniform diameter throughout and extend substantially parallel to one another longitudinally of the shelter.

11. An inflatable shelter comprising a sectional covering having a series of sections of flexible impervious sheet material extending from end to end of the shelter with margins in juxtaposition, slide fastener means including a flexible sealing element on said margins for separably joining and closing the margins, a supporting framework of interconnected inflatable tubular elements for maintaining said sectional covering upright to provide sidewalls and roof of the shelter, means for inflating said framework, said framework having one of said inflatable tubular elements disposed at each end of the shelter and extending transversely of the shelter along said covering in supporting attached relation thereto, and an end wall of flexible impervious sheet material attached to each of the last said tubular elements and extending continuously across the end of the shelter for closing the same, one of the end walls having an opening therein for entrance into the shelter and means for closing said opening.

12. An inflatable shelter comprising a basic individual sectional structure comprising a covering section of flexible impervious sheet material having ends and an inflatable main frame of interconnected inflatable tubular elements for maintaining said covering section upright to provide sidewalls and roof of the shelter, one of said tubular elements extending transversely of the shelter along said covering section at an end thereof in supporting attached relation thereto and supporting a wall of flexible impervious sheet material in dependent disposition at said end of said covering section for closing the end of the shelter, and supporting and closing means for attachment to said sectional structure at the other end of said covering section, said means comprising an inflatable tubular element extending transversely of the shelter along said covering section at said other end thereof for supporting the same and having a wall of flexible impervious sheet material attached thereto and dependent therefrom for closing the other end of the shelter, and means for separably attaching the first said means to said basic individual sectional structure.

13. An inflatable main frame for a sectional supporting framework adapted to maintain upright a flexible sectional covering of a shelter, said main frame comprising an inflatable tubular element of inverted generally U-shaped configuration having closed ends for disposition upright and transversely of the shelter in substantially conforming supporting relation to a section of the covering, the legs of the U providing support for the sidewalls of the shelter and the base of the U providing support for the roof of the shelter, and a plurality of inflatable tubular ele-

13

ments spaced-apart along the U-shaped element in communication therewith and projecting therefrom at a side thereof longitudinally of the shelter and terminating in closed ends for attachment to an adjacent section of said framework and for disposition in supporting relation to the sidewalls and roof portion of said section of the covering.

14. An inflatable main frame as defined in claim 13 in which the U-shaped tubular element is of greater diameter as compared to that of said plurality of inflatable tubular elements, and said plurality of inflatable tubular elements are of substantially uniform diameter throughout and extend longitudinally of the shelter in spaced-apart substantially parallel relation one to the other.

15. An inflatable main frame as defined in claim 13 in which the U-shaped tubular element

14

has the legs of the U and the base of the U each tapering inwardly from their midpoints toward their ends, and the longitudinally-extending tubular elements project from said U-shaped tubular element at the junctions of said legs with said base of the U and also at said midpoints of the legs and base of the U.
